(57) **CLAIM**

I claim the ornamental design of equipment for accident prevention, as shown and described.

DESCRIPTION

FIG. 1 is a perspective first view of a design for accident prevention equipment in accordance with the invention.

FIG. 2 is a perspective second view of a design for accident prevention equipment in accordance with the invention.

FIG. 3 is a perspective third view of a design for accident prevention equipment in accordance with the invention.

FIG. 4 is a perspective first view of component parts of the accident prevention equipment shown in FIGS. 1-3.

FIG. 5 is a second view of component parts of the accident prevention equipment shown in FIGS. 1-3.

FIG. 6 is a perspective view of a first component part of the accident prevention equipment shown in FIGS. 1-3; and, FIG. 7 is a perspective view of a second component part of the accident prevention equipment shown in FIGS. 1-3.

The ornamental design which is claimed is shown in solid lines in the drawings. The broken lines in the drawings are for illustrative purposes only and form no part of the claimed design.
